(57) **CLAIM**

The ornamental design of a bouquet jewel, as shown and described.

DESCRIPTION

FIG. 1 is a perspective view of a bouquet jewel showing my new design, shown in use with a stephanotis flower;

FIG. 2 is a perspective, exploded view thereof;

FIG. 3 is an enlarged perspective view of the jeweled element thereof; and,

FIG. 4 is a side elevation view thereof.

The broken lines showing of a stephanotis flower and tube section is for illustrative purposes only and forms no part of the claimed design.
